UNITED STATES PATENT OFFICE.

MARTIN TWORSKI, OF POWELL RIVER, BRITISH COLUMBIA, CANADA.

DESIGN FOR A WATCHCASE WITH MIRROR.

Application filed July 28, 1924. Serial No. 10,272. Term of patent 14 years.

To all whom it may concern:

Be it known that I, MARTIN TWORSKI, a citizen of Poland, residing at Powell River, in the Province of British Columbia and Dominion of Canada, have invented a new, original, and ornamental Design for a Watchcase with Mirror, of which the following is a specification.

Fig. 1 is a front face view of a watch case with mirror showing my design.

Fig. 2 is a perspective view of a watch case with mirror showing my design on the inside of the outer covers.

Fig. 3 is a perspective view of the same showing my design on the rear and inside plates.

I claim:

The ornamental design for a watchcase with mirror as shown.

In testimony whereof I have affixed my signature.

MARTIN TWORSKI.
